UNITED STATES PATENT OFFICE.

ANDREW J. LLOYD, OF BOSTON, MASSACHUSETTS.

FIELD-GLASS.

No. 802,817.

Specification of Letters Patent.

Patented Oct. 24, 1905.

Application filed March 29, 1905. Serial No. 252,748.

To all whom it may concern:

Be it known that I, ANDREW J. LLOYD, a citizen of the United States, residing at Boston, in the county of Suffolk and State of Massachusetts, have invented a new and useful Improvement in Field-Glasses, of which the following, taken in connection with the accompanying drawings, is a specification.

My invention relates to the focus adjustment of field or opera glasses; and it consists of a mechanism which will permit of adjusting each eyepiece to the user's eye, allowing for the focal characteristics of each eye, and then moving both eyepieces to adapt the combined eyepieces to the distance of the object to be observed. The mechanism for obtaining this result is illustrated in the accompanying drawings, in which—

Figure 1 shows in elevation a field-glass of the Zeiss class. Fig. 2 shows an end view of the same. Fig. 3 is a sectional view showing the eyepieces and their connected parts.

In the drawings, A and B represent the body parts of the instrument, and G and G' the eyepieces, or, rather, the parts that are moved in adjusting the focal lengths to the different eyes and also to the distance of the object to be observed.

K and K' are sprocketed rings connected to the eyepieces and adapted to engage with the sprocket-chain L, whereby the turning of one of the eyepieces will cause a corresponding rotation of the other.

To adapt the instrument to the interocular distance, the parts A and B are connected together by pivoted bars C C', and D D'. The parts C and C' and D and D' overlap each other, as shown in Figs. 1 and 3, and are clamped together by means of the central tube E and a screw-rod E'. The loosening of the screw-rod E' will free the parts C and C' and also the parts D and D' and admit of adjusting the distance between the body parts A B—

that is, the interocular distance—and by tightening the screw-rod E' the parts may be firmly held in the desired positions.

To adjust the separate eyepieces to the eyes, the spiral grooves H H' are made in the movable tubular parts and pins are set in the corresponding fixed tubes and are adapted to engage with the said grooves H and H', so that by turning the external parts of the eyepieces the adjustment for the individual eye is made.

The length of the sprocket-chain is adapted to the sprocket-rings when the interocular distance is greatest. When the body parts A and B are brought nearer to each other in adjusting them to a shorter interocular distance, the chain L will be slack, but not enough to prevent its working, as the sprocket-teeth are made comparatively long, and although the chain is slack it will still perform its function.

In practice the eyepieces are adjusted to the characteristics of the user's eyes before the sprocket-chain L is connected to the instrument. Then the chain is placed upon its sprockets and the field-glass is adjusted to the distance of the objects to be observed. Thus the personal adjustment remains permanent and is not affected by the object-distance adjustment.

I claim—

In a binocular instrument of this class; eyepieces independently adjustable having attached sprocketed rings; and a sprocket-chain constructed to engage with said sprocketed rings; substantially as and for the purpose set forth.

In testimony whereof I have signed my name to this specification, in the presence of two subscribing witnesses, on this 25th day of March, A. D. 1905.

ANDREW J. LLOYD.
